UNITED STATES PATENT OFFICE

2,469,553

SPRAY DRIER APPARATUS

Joseph M. Hall, Chicago, Ill., assignor to Drying
& Concentrating Company, a corporation of
Delaware

Application June 14, 1943, Serial No. 490,739

8 Claims. (Cl. 159—4)

1

This invention relates to an apparatus for and a method of dehydrating liquid products.

One of the objects of the invention is the provision of a new and improved system of dehydration in which comparatively dry steam at low pressure is caused to circulate in a single dehydrating chamber for dehydrating a liquid product sprayed into said chamber.

Another object of the invention is the provision of a new and improved dehydrating chamber having novel means for recirculating the drying medium within the chamber.

A further object of the invention is the provision of a new and improved method for dehydrating a liquid product in a single continuous operation.

Another object of the invention is the provision of a new and improved dehydrating chamber within which the drying medium is heated and circulated for dehydrating a liquid product discharged therein.

Another object of the invention is the provision of a new and improved dehydrating chamber having means whereby the entire dehydrating operation is performed within a single chamber, including the heating of the drying medium.

A further object of the invention is the provision of a new and improved system that is simple in construction, composed of few parts, comparatively inexpensive to install, and that is efficient in operation.

Other and further objects and advantages of the invention will appear from the following description, taken in connection with the accompanying drawings in which

Fig. 1 is an elevation of the dehydrating system, shown more or less diagrammatically;

Fig. 2 is a plan view of an upper portion of the same, with parts broken away;

Fig. 3 is an enlarged view of the heating, spraying and circulating assemblies, with parts broken away and parts in section;

Fig. 4 is a view similar to Fig. 3, but showing a modified form of construction;

Fig. 5 is a perspective view of a portion of the spray head or fan, with parts in section and parts omitted for the sake of clearness;

Fig. 6 is a section on the line 6—6 of Fig. 5; and

Fig. 7 is a section on the line 7—7 of Fig. 5.

It is common practice, in the dehydrating art, to employ mechanism for concentrating and dehydrating liquid products in a plurality of stages. It is also conventional to heat the drying medium at points without the concentrating or dehydrating chamber, and to conduct the heated medium

2

to the concentrating chamber in either an open or closed circuit. Such systems necessitate the use of an apparatus that is more or less complicated and requires a plurality of dehydrating chambers and separate heating mechanism.

The present invention seeks to concentrate and simplify the construction, and to provide a system in which the drying medium is steam that is generated in a single drying chamber and recirculated within such chamber, together with means for continually removing excess steam or vapor from the system and for maintaining a partial vacuum within the dehydrating chamber.

Referring now to the drawing, the reference character 10 designates a dehydrating system, the essential features of which comprise a dehydrating chamber 11 having mounted on its upper portion a heating assembly 12 for heating the drying medium, a circulating assembly for recirculating the drying medium 13 within the dehydrating chamber, a spraying assembly 14 for spraying the liquid product in the dehydrating chamber, an exhaust fan or vacuum pump 15, operated by a motor 20, for maintaining the interior of the dehydrating chamber at a reduced atmospheric pressure, a reservoir 16 containing the liquid product to be evaporated, and a pump 17 for supplying the liquid product to the dehydrating chamber.

15 The dehydrating chamber 11 has an upper cylindrical portion 18, a lower tapered portion 19, and a lower tapered extension 21. The upper portion of the chamber is provided with a top wall or closure 22 which may incline upwardly toward the axis of the chamber. It is provided with an axial opening 23 over which is mounted a cylindrical heating assembly comprising a casing 24, having a top wall 25 which is provided with a restricted axial opening 26 through which vapor

20 evaporated from the liquid product is conducted, as will presently appear. Mounted on the side and top of the casing 24 are a plurality of electrical heating units 27, 28, for heating the recirculated vapor or drying medium, as will presently be described. Other electrical heating units 29 are mounted on the top wall 22 of the dehydrator adjacent to the heating assembly member 24. These heating elements create a heating zone within and adjacent to the casing 24, through

25 which the drying medium is caused to circulate during the operation of the apparatus for superheating such medium.

30 Suitable means are provided for causing the recirculation of the drying medium within the dehydrating chamber 11. As shown, this assem-

35

40

45

50

55

bly 13 comprises a cylindrical, tubular, directing or guide member 31, having its upper portion return bent in a curve, as at 32, and with its lower edge attached to the lower edge of the tubular member 31, thus forming a double wall enclosing an annular space 300 tapering downwardly. It will thus be seen that the upper edge of the guide member 31 is a smooth curve between which and the side walls of the casing 24 an annular passage 50 is provided through which the drying 10 medium is adapted to flow.

Suitable means are also provided for causing the vapor generated in the chamber 19 to flow upwardly through the cylindrical chamber 31. As shown, this is accomplished by the spray member, which also functions as a fan, as will now be described. The spray assembly comprises a shaft 33 extending downwardly axially through the cylindrical member 31, and constitutes an elongation of the armature shaft of the motor 34 mounted above the heating assembly member 24. This shaft is surrounded and protected by a casing 35, which is connected to a conical deflector 36, which in turn is connected with the casing of the motor 34.

Attached to the lower end of the shaft 33, and rotatable therewith, is a cast steel spray head or hub 37, which is hollow and has integral therewith vanes or blades 38 extending outwardly therefrom. These vanes 38 are flattened and, with the head 37, form a fan for recirculating the drying medium within the dehydrating chamber 11. A tube 38^a for the liquid product extends along the leading edge of each vane or blade, and is secured in the head and welded to the vane for conducting the liquid product from the head to the nozzles 41. These nozzles are detachably connected to the outer ends of the corresponding tubes. In order that the flow of drying medium through the fan shall be uniform throughout the diameter of the fan, the blades 38 are made to taper in width toward their outer ends, and the angle of the blade faces to the horizontal is greater at their inner than at their outer portions. The difference in width and angularity compensates for the different speeds of these portions.

The armature shaft 33 is hollow, and a pipe 42 is in communication therewith for conducting the liquid product from the reservoir 16 to the spray head. The liquid product may be delivered to the spray head by means of a pump 43, operated by a motor 44, as is usual in such constructions. The arms 38 of the spray are in the form of fan blades which are adapted to direct the vapor or drying medium upwardly through the cylindrical member 31, and, due to the restricted opening 26, cause a greater portion of the drying medium to be directed downwardly between the casing 24 and the directing or guide member 31.

In order to cause the drying medium to rotate in its downward movement, the cylindrical directing or guide member 31 is provided on its outer surface with inclined or spiral vanes 45, which are rigidly attached to the return bent wall 32 of the cylindrical member 31. These vanes are also attached at their outer edges to the wall of the casing 24 for holding the parts in assembled relation.

It is desirable that the pressure within the chamber be below atmosphere in order to accelerate the evaporation of the sprayed particles. An exhaust fan 15, operated by a motor 20 for lowering the pressure in the dehydrating chamber and for exhausting excess steam therefrom, is provided for this purpose. The intake of this 75

fan is in communication, through a pipe 46, with a snail or chamber 47 surrounding the cone-shaped member or shield 48 and over the restricted opening 26, as shown more clearly in Fig. 5 of the drawing. The pipe 46 is attached tangentially to the chamber 47 in such a manner as to cause the exhaust vapor to rotate in the same direction as in the dehydrating chamber 11, so as to avoid turbulence. The pipe 46 may be provided with an adjustable valve 40 for controlling the proportionate amount of steam exhausted through the pipe 46.

In the operation of the device, the liquid product is pumped from the reservoir 16 and delivered to the spray head 37, which is rotated by the motor 34, and this rotation sprays the liquid product into the upper portion of the dehydrator chamber, as indicated in Fig. 1 of the drawing. After the apparatus has been running a few minutes practically all of the air will have been replaced by steam or vapor evaporated from the product, and the drying medium will then be entirely vapor or steam. This steam will be caused to move upwardly through the axial passage of the guide member 31, and a portion of the steam will be exhausted by the fan 15 through the passage 26, and the remainder and larger portion of the steam will pass over the upper end of the tubular member 31 and downwardly between the vanes 45, which will cause the air to rotate and move across the nozzles 41 for dehydrating the liquid product.

In passing upwardly through the tubular member 31, and then downwardly through the passage 50, the vapor will have its temperature very much increased as it passes through this heated zone of the chamber, and will move downwardly in an outer spiral adjacent the side walls of the chamber, and then reverse and flow upwardly in 40 the same spiral direction in an inner spiral up to the tubular member 31, thus completing its cycle of movement. The fan 15 is operated at such velocity, and is of such capacity, and the valve 40 adjusted to such a position, that the pressure within the chamber is maintained below atmospheric.

The nature of the product to be dehydrated, and the percentage of moisture to be left in the dehydrated product, will determine, to a large 50 extent, the most efficient conditions to be maintained within the dehydrator chamber during the dehydrating operation.

It has been found in evaporating milk, for instance, that the reduction of the pressure to about 10" of mercury, and with the drying medium at 190° F., substantially the same results are obtained as heating the medium to 240° F. and operating at atmospheric pressure. Satisfactory results in dehydrating milk, for example, may be obtained by preserving a partial vacuum within the chamber and adjusting the device so that the medium enters the heating zone at around 150° F. and leaves it at around 400° F. The evaporation of the moisture from the sprayed particles prevents them from becoming injured by the heat, and by the time the particles are dehydrated the medium has cooled below the temperature at which the dehydrated particles would be injured.

The lower portion of the chamber 11 may be, 70 and preferably is, provided adjacent the tapered portion 21 with a directing cylinder 48, having a shield 48^a surrounding the member 48, both of which are coaxial with the chamber and supported in any suitable manner, as by means of arms or brackets 49. The shield 48^a terminates

inwardly of the side walls of the chamber 11 for forming an annular passage 60. The drying medium passes downwardly on the outside of the cylinder through the passage 60, and the inner spiral of drying medium passes up through the cylinder, as indicated in Fig. 1 of the drawing. The dehydrated material is thrown outwardly against the walls of the tapered portion of the chamber by centrifugal action, and slides by gravity downwardly along the dehydrating chamber walls, as is usual in such constructions.

A suitable rotating valve 51, operated by a motor 52, is provided below the tapered portion 21 and discharges the dehydrated material into a screen 53 operated by a vibrator 54, which in turn is actuated by a motor 55 in the usual manner. The screened material may be discharged into a receptacle 56, which may rest on a scale 57 for weighing the material. If desired, a thermometer 58 may be placed in the cylindrical portion of the dehydrator, and this thermometer has an indicator 59 accessible to the operator.

The form of construction shown in Fig. 4 differs from that disclosed above in that the liquid product is sprayed into the dehydrator chamber by a plurality of fixed spray nozzles 61, under pressure, instead of by means of a rotating head, as in the previous construction. In this form of the device the means for creating a heating zone in the dehydrating chamber is the same as in the construction shown in Figs. 1 and 3, but the liquid product in the container 16 is delivered to what may be termed a header 62 under pressure by a centrifugal pump 63.

The construction of the tubular member 31^a and the arrangement of the vanes 45^a is substantially the same as that previously described. The header 62 is mounted in the upper portion of the space 300^a between the inner and outer walls of the tubular member 31^a, and has a plurality of depending branch conduits 64 each of which is provided with a nozzle 61 extending outwardly below the outer wall 67 of the member 31^a.

The inner cylindrical wall 66 of the tubular directing member 31^a is extended downwardly beyond the outer curved wall 67, and is flared outwardly, as at 68, below the nozzles 61, for directing the gaseous drying medium outwardly. The lower edge of the outer wall 69 of the guide member 31^a is also flared outwardly for directing the drying medium across the ends of the nozzles 61.

By means of this arrangement the liquid product being forced radially outwardly through the nozzles 61, is broken up into very fine particles, and these particles are dehydrated by the rotating column of a drying medium which, in the present instance, is vapor or dry steam at high temperature but low pressure. The steam is recirculated by means of a fan 65, which is secured to the lower end of the motor shaft 33, within but adjacent to the upper end of the member 31^a. The operation of the device is similar to that already described, and it is not thought necessary to repeat the same.

It will thus be seen that the drying medium is heated within the dehydrating chamber, and that it is recirculated within said chamber. The drying medium is derived from the moisture evaporated from the liquid product and is superheated in the heating zone and preferably maintained at sub-atmospheric pressure during the operation of the device. The temperature and pressure may each be adjusted to meet the requirements of any particular product that is being dehydrated.

It is thought from the foregoing, taken in connection with the accompanying drawings, that the construction and operation of my device will be apparent to those skilled in the art, and that changes in size, shape, proportion and detail may be made without departing from the spirit and scope of the appended claims.

I claim as my invention:

1. In a dehydrating system, a dehydrating chamber, a heating zone in the upper portion of said chamber, means for heating said zone, means for circulating and recirculating a drying medium in said chamber through said zone, said means comprising a tubular guide member arranged axially of said chamber in the upper portion thereof within said zone, angularly arranged baffles on the exterior of said member for causing the medium moving down across the same to move downwardly within said chamber in an outer spiral, a rotating spray head immediately below said member for spraying said product into the downwardly moving drying medium, fan blades carried by said head for causing said downwardly flowing medium to reverse and flow in an inner spiral upwardly through said member over the top thereof and then downwardly externally thereof through said heating zone, and means for exhausting vapor extracted from said product and for reducing the atmospheric pressure within said chamber.
2. A dehydrating chamber comprising an upper cylindrical portion, a lower tapered portion, said cylindrical portion having a top wall with an axial opening therethrough, a casing over said opening, a tubular member extending into said opening and spaced downwardly and inwardly from said casing, a nozzle head rotatably mounted just below said member and having arms in the form of fan blades with nozzles on the outer ends of said arms for spraying a liquid product into said chamber and for causing the recirculation of a drying medium upwardly through said member and downwardly between said member and casing and across said nozzles, means on said member for causing said medium to flow downwardly in an outer spiral, and means for superheating said medium as it is recirculated within said chamber just prior to its passage across said nozzles.
3. A combined fan and distributor member comprising a hollow head member for receiving a liquid product to be dehydrated, vanes extending radially therefrom, tubular members along the leading edge of each vane, and a spray nozzle at the end of each tubular member, said vanes tapering in width toward their outer ends and having their side faces at a greater angle to the horizontal at their inner ends than at their outer ends, whereby the velocity of the air flowing through the fan is uniform throughout the diameter of the fan.
4. In a dehydrating system, a dehydrating chamber, a heating zone in the upper portion of said chamber, means for heating said zone, means for circulating and recirculating a drying medium in said chamber through said zone, said means comprising a tubular guide member arranged axially of said chamber in the upper portion thereof within said zone, means including baffles for causing the drying medium that moves upwardly through the guide member and through the heating zone to be thereafter directed downwardly in an outer spiral, a rotating spray head immediately below said member for spraying said product into the downwardly moving drying

medium, fan blades carried by said head for causing said downwardly flowing medium to reverse and flow in an inner spiral upwardly through said member over the top thereof and then downwardly externally thereof through said heating zone, and means for exhausting vapor extracted from said product.

5. A dehydrating chamber comprising an upper cylindrical portion, a lower tapered portion, said cylindrical portion having a top wall with an axial opening therethrough, a casing over said opening, a tubular member extending into said opening and spaced downwardly and inwardly from said casing, a nozzle head rotatably mounted just below said member and having arms in the form of fan blades with nozzles on the outer ends of said arms for spraying a liquid product into said chamber and for causing the recirculation of a drying medium upwardly through said member and downwardly between said member and casing and across said nozzles, and means for heating said medium as it is recirculated within the chamber and baffles for imparting to the thus heated medium a downward spiral motion immediately prior to its passage across said nozzle.

6. In a system for dehydrating a material, a dehydrating chamber of circular cross section with smooth interior side walls and normally containing only said material and vapor derived therefrom, means including a tubular guide member, a fan and stationary deflector blades, all mounted in the central upper portion of said chamber to force vapor derived from said material in a stream extending centrally upwardly and subsequently extending outwardly toward the side walls of the chamber in a spiral manner thereby providing a closed path of vapor circulation in the chamber, a heat transfer zone located entirely within the central upper portion of the chamber and including heat exchange surfaces for heating the vapor prior to said outward flow, means for supplying heat to said heat transfer surfaces, and means to spray said material centrally outwardly into said stream in that portion thereof wherein the vapor is moving in a downward spiral path.

7. In a system for dehydrating a material, a dehydrating chamber of circular cross section with smooth interior side walls and normally containing only said material and vapor derived therefrom, means including a tubular guide member, a fan and stationary deflector blades, all mounted in the central upper section of said chamber to force vapor derived from said material in a stream extending centrally upwardly and subsequently extending outwardly toward the side walls of the chamber in a spiral manner thereby providing a closed path of vapor circulation in the chamber, a heat transfer zone located

entirely within the central upper portion of the chamber and including heat exchange surfaces for heating the vapor prior to said outward flow, means for supplying heat to said heat transfer surfaces, means to spray said material centrally outwardly into said stream in that portion thereof wherein the vapor is moving in a downward spiral path, and means for diverting and exhausting from the chamber a sufficient portion of the stream to maintain a sub-atmospheric pressure in the chamber.

8. In a system for dehydrating a material, a dehydrating chamber of circular cross section with smooth interior side walls and normally containing only said material and vapor derived therefrom, means including a tubular guide member, a fan and stationary deflector blades, all mounted in the central upper portion of said chamber to force vapor derived from said material in a stream extending centrally upwardly and subsequently extending outwardly toward the side walls of the chamber in a spiral manner thereby providing a closed path of vapor circulation in the chamber, a heat transfer zone located entirely within the central upper portion of the chamber and including heat exchange surfaces for heating the vapor prior to said outward flow, means for supplying heat to said heat transfer surfaces, means to spray said material centrally outwardly into said stream in that portion thereof wherein the vapor is moving in a downward spiral path, and means for diverting and exhausting from the chamber a sufficient portion of the stream to maintain a sub-atmospheric pressure in the chamber, said last named means including an exhaust duct secured to and emerging from the chamber at a point above the tubular guide member.
